(57) **CLAIM**

We claim the ornamental design for a vacuum cleaner, as shown and described.

DESCRIPTION

FIG. 1 is a perspective view of a vacuum cleaner showing our new design.

FIG. 2 is another perspective view of the vacuum cleaner of FIG. 1.

FIG. 3 is a front side view of the vacuum cleaner of FIG. 1.

FIG. 4 is a rear side view of the vacuum cleaner of FIG. 1.

FIG. 5 is a left side view of the vacuum cleaner of FIG. 1.

FIG. 6 is a right side view of the vacuum cleaner of FIG. 1.

FIG. 7 is a bottom side view of the vacuum cleaner of FIG. 1; and,

FIG. 8 is a top side view of the vacuum cleaner of FIG. 1. The broken lines in the drawings depict portions of the vacuum cleaner that form no part of the claimed design.
